UNITED STATES PATENT OFFICE.

ASHER M. WALTER, OF EASTON, PENNSYLVANIA.

GAS-ENGINE AUXILIARY.

Application filed September 29, 1922. Serial No. 591,248.

To all whom it may concern:

Be it known that I, ASHER M. WALTER, a citizen of the United States, residing at Easton, county of Northampton, and State 5 of Pennsylvania, have invented certain new and useful Improvements in Gas-Engine Auxiliaries, whereof the following is a specification, reference being had to the accompanying drawings.

10 This invention relates to auxiliaries for internal combustion engines, and the object thereof is to provide a device for permitting the introduction of air into the cylinder during operation in automatically controllable quantities and in such manner as to accomplish certain advantages among which are the increase of power by the more efficient consumption of the fuel, reduction in carbon deposits, economy in the consumption 15 of oil and fuel, and other advantages which will become apparent as the nature of the invention is more fully disclosed.

Another object of the invention is to provide a device for the purpose set forth which 20 is adapted to be inserted in the opening of an internal combustion engine usually provided for the priming cup, and embodying a priming cup in its assembly so as to secure the advantages mentioned above while retaining the use of a priming device.

These and other objects are accomplished by what I now regard as the preferred embodiment of my invention from among other forms and arrangements embraced within 25 the spirit of the invention and the scope of the appended claims.

In the accompanying drawings, Fig. I is a view in section of a combined priming and auxiliary air feeding device constructed 30 in accordance with the present invention.

Fig. II is a view in transverse section taken on the line II—II of the preceding figure; and

Fig. III is a view in section taken on the 35 line III—III of Fig. I.

The invention embodies in its essentials a priming valve of the type generally employed in engines for motor vehicles, and an air feeding device associated therewith.

40 The air feeding device comprises a four-way casting 10 or cross-coupling consisting of the longitudinal member 11 having the bore 12 and the transverse member 13 provided with the intersecting bore 14. The 45 ends of the longitudinal member are threaded internally at 15 a threaded nipple 16 ap-

propriate for introduction into the opening of an engine cylinder being inserted in one of said threaded ends.

The customary priming cup employed in 60 motor vehicle engines may be removed and the present device substituted. To that end the portion 16 should be threaded to a corresponding pitch so as to be received in gas-tight engagement. The priming device of 65 conventional type is indicated generally at 17 and includes a reduced and threaded end 18 which is inserted in the threaded end 15 of the cross coupling. The priming device is formed at its opposite end with a cup 70 member 19 draining into a longitudinal bore 20 which communicates with the bore 14, a valve 21 being fitted into the device and adapted to control the passage of fluid through the bore 20 and to effect a closure. 75

The auxiliary air feeding arrangement 80 comprises a pair of plugs 22 each of which is reduced at one end forming a shoulder and threaded as at 23 for introduction into its corresponding end of the cross member 13 of the four-way casting. A copper gasket 85 may be introduced between said shoulder of the plug and the end of the cross-coupling to make a gas-tight joint. The exposed end of the plug is angularly formed to facilitate 90 the application of a wrench. Each plug is formed with a continuous bore 24 or channel extending throughout and disposed horizontally during use of the device communicating at their inner ends with the interior of 95 the cross coupling and at their opposite ends with the atmosphere by means of slightly reduced aperture 25. The bore and aperture 100 may be conveniently formed by drilling the plug, inserting the drill into the reduced end first and drilling until the point of the drill begins to break through the opposite end of the plug, whereupon the drill is removed. This operation results in the formation of a slight bevel at the juncture of the bore and aperture for cooperation with a spherical valve 26 which is subsequently inserted into the bore. The spherical valve should be of a diameter to loosely fit the bore but to effect 105 a checking closure by contact with the surface of the bevel portion thus closing the aperture under the influence of pressure within the device. For the purpose of limiting movement of the valve in the bore a pin 27 is extended across the bore and is 110 preferably spaced very closely to the valve so that when the valve is closed in tight en-

gagement against its seat its distance from the pin will be in the neighborhood of 1/64 of an inch.

In the operation of the device when properly associated with an internal combustion engine in the manner stated, the rise in pressure created during each compression stroke being communicated to the interior of the cross-coupling will effect a closure or seating of the ball valves so as to prevent the escape of pressure, but during an intake stroke the ball valves will be unseated permitting the entrance of small quantities of air past the valves and ultimately into the engine cylinder. The quantity of fresh air permitted to enter is very small but sufficient to insure the production of the advantages noted, such as the complete combustion of the fuel and a reduction in carbon deposition.

It will be apparent that if the degree of vacuum in the engine cylinder during an intake stroke is light the valves will be unseated only slightly admitting only a quantity of air sufficient to accomplish the desired results, as when the engine is operating under an open throttle. When the engine intake is heavy the valves will be unseated to a greater extent permitting the entrance of a maximum amount of air. It will be noted that the arrangement in no way interferes with the introduction of priming fluid into the cylinder when necessary, and without necessitating the removal of the air feeding device. The use of springs is avoided as the ball valves are controlled solely by the influence of engine compression and suction.

Having thus described my invention, I claim:

1. In an auxiliary air-feeding and priming device for internal combustion engines, the combination of a multiple-way coupling for connection into an engine cylinder, a plurality of plugs fitted into said coupling having horizontal channels and orifices for admitting air to the cylinder, and

ball valves adapted by limited movement to open and close the aforesaid orifices under the influence of engine compression and suction respectively.

2. A priming and auxiliary air feed device for internal combustion engines comprising a four-way coupling one terminal whereof is adapted to serve as a priming cup, a plug inserted in each of a pair of axially opposed terminals, each said plug having a bore with a reduced inlet orifice, a ball valve in each channel for controlling its respective inlet orifice, and means insuring a limited movement at all times of said ball valve under the influence of varying engine compression and suction.

3. In a combined priming and auxiliary air feeding device for internal combustion engines, the combination of a four-way coupler having aligning horizontal bores, a plug removably inserted in each said horizontal bore and having a reduced inlet orifice, a ball valve in each channel adapted to seat against the reduced inlet orifice, and means insuring a very limited movement at all times of said ball valves under the influence of engine compression and suction.

4. In a combined priming and auxiliary air feeding device for internal combustion engines, the combination of a four-way coupler having opposed horizontal channels, a plug removably inserted in each said channel and having a reduced inlet orifice, a ball valve in each channel adapted to seat against the reduced inlet, and a transverse pin in each plug adapted to limit the movement at all times of its associated ball valve under the influence of engine compression and suction.

In testimony whereof, I have hereunto signed my name at Easton, Pennsylvania, this twenty-fifth day of September, 1922.

ASHER M. WALTER.
